CORNER MOUNT AND METHOD OF MAKING SAME

Application filed March 13, 1926. Serial No. 94,568.

This invention relates to corner mounts for attaching cards, photographs and similar articles to albums and flat surfaces and relates more particularly to a closed corner mount and to the method of making the same.

Heretofore, corner mounts have been made in flat form and sold in that condition requiring the user to fold the same upon certain lines in order to form a complete mount with a corner-receiving pocket. Because of the small size of the mounts, the operation of folding and securing the various folds in permanent position by moistening the adhesive on certain portions of the corner has been a very tedious and nerve-racking task requiring infinite patience and pains. The sales of such corners in flat form have been much restricted because the users were unwilling to expend the time and patience required in the folding operation. Furthermore, it was rather difficult to fold the corner exactly on the scored line because of its small size and unless folded on the scored line it detracted from the attractive appearance of the corner in many cases.

Another difficulty encountered in the use of such mounts is in accurately positioning the four mounts on the supporting surface. Unless they are disposed with such exactness that the four corners of the card or other object project into the pockets to the fullest extent any subsequent curling of the card tends to withdraw the corners from said pockets and to cause the card to become detached or separated from the mounts. The only feasible way to secure exact positioning of the mounts on the album page or other supporting surface is to place mounts on the four corners of the card, taking care that each corner of the card projects to the fullest possible extent into the pocket on the mount, and then to moisten the adhesive coated backs of the mounts and to press the card and mounts down upon the supporting surface. Mounts of this character heretofore made, however, have not been of a form of construction permitting this operation to be carried out because the mounts when placed on the card corners were more or less loose thereon and easily fell off or became disarranged in the handling of the card.

Therefore, the main object of my invention is the provision of a corner mount which is folded or closed and ready for instant use and which may be applied to the supporting surface upon which it is to be mounted, whether 55 a book, album, or other object by merely moistening the adhesive coated back of the mount.

Another object of the invention is the provision of a mount so constructed that when placed in proper position on the corner of a card or other similar object, the corner of the latter will be held firmly gripped within the mount pocket to insure its retention in position on the card and to permit the latter to be freely handled without disturbing said position. 65

A further object of the invention is the provision of a method for making a closed or folded corner mount at a very low cost and in a finished condition ready for use. 70

Other objects of the invention will be more specifically set forth and described hereinafter.

My invention contemplates a corner mount having a body portion coated with adhesive on its back face and provided with a corner receiving pocket and ready for instant application to a supporting surface on the moistening of its adhesively coated back. The invention further contemplates a cheap, simple and efficient method for making the mounts consisting in forming the body portion of the mount from a continuous strip of adhesively coated material, the end of the strip being squared off and the two sharp corners cut off on angles of forty-five degrees with the axes of said strip, after which the two corner edges are folded over upon the body portion into a right-angled relation to each other to start the pocket which is then completed by the application of a right-angled cap cut out of a second continuous strip of suitable material. The cap is preferably applied while in a moist condition so it readily adheres to the coated outer faces of said flanges. When 85 completed the mount is cut off the continuous body strip in such a manner as to leave the end of the strip of a shape proper for the formation of the next succeeding corner. 95

One of the important features of my in-

vention consists in embossing the pocket portion of the mount to form projecting ridges upon the inner surface of the cap within the pocket and corresponding depressions in the body portion thereof. The embossing should be sufficiently deep to impress all the layers of that portion of the mount, in consequence of which the ridges on the inner face of the cap lock into the corresponding depressions in the body portion and when the corner of the card is inserted in the pocket the ridges grip and hold it thereby retaining the mount in firm position on the card. This feature is of great advantage because it permits the mounts to be positioned on the supporting surface with exactness since the mounts when placed on the corners of the object to be mounted will grip the same and retain their position even when the object is freely handled.

In the accompanying drawings, illustrating the preferred embodiment of my invention, Figure 1 is a plan view of the end of a continuous strip from which the body portion of the corner mount is formed, the broken lines indicating the lines of fold for the turning over of the two initial flanges; Fig. 2 is a similar view showing the flanges turned over to start the formation of a corner receiving pocket; Fig. 3 is a plan view of a second continuous strip from which the cap is cut out showing the form of the cap; Fig. 4 is a view similar to Fig. 2 but after the application of the cap to the flanges and showing the mount completed with the line of separation from the first continuous strip; Fig. 5 is a plan view of the completed mount; Fig. 6 is a sectional view on line 6—6 in Fig. 5 and on an enlarged scale; Fig. 7 is a view similar to Fig. 6 showing the corner of a card inserted in the mount; Fig. 8 is a view in perspective of a complete corner mount; and Fig. 9 is a plan view of the back or reverse face of the completed mount.

Referring to the drawings, 10 indicates the body portion of one form of mount having straight sides 12 and a corner receiving pocket 14 which is right-angled for receiving and fitting the squared corner of a card or similar object. The side edges of the pocket lie at angles of forty-five degrees to the sides 12. The pocket may, if desired, be triangular in plan, but it is preferably right-angled in order to avoid covering any portion of the picture in the card and to increase its attractiveness in appearance when mounted. The pocket 14 is formed integral with the body portion 10 by turning over two contiguous edges of the latter into a right-angled relation with each other and then applying thereto a right-angled cap which is preferably made of two or three plies to impart stiffness and durability thereto, and to permit the mounted card to be removed there-

from and replaced at will without danger of tearing or injuring the pocket. Since the corner mount is necessarily made of comparatively thin paper the pocket unless stiffened by a cap of comparatively heavy material is very easily torn and injured in the mounting operation or afterward in handling the album or other supporting surface. Heretofore, this has been one objection to a corner mount formed of one folded piece. Furthermore, the cap must be substantially coextensive with the flanges of the pocket for if the latter extend but a part way from the fold to the edge of the pocket, the latter is thereby weakened and it is open to the additional objection that the edge of the card or print may encounter the edges of the flanges and either prevent the full entrance of the card and injure the mount or buckle the card or print.

The form of the bottom edge 16 of the body portion of the mount is more or less immaterial so long as the body portion is of sufficient size to secure a proper bond between it and its supporting surface. When made from a continuous strip, however, it is convenient to cut off the completed corner on a line 16 which will leave the end of the strip properly shaped for the forming of the next mount. The back face of the corner mount is coated with any suitable adhesive.

The pocket portion of the mount is embossed in any suitable manner, the embossed lines being preferably arranged to form a design to enhance its appearance. In the form shown in the drawings the embossing comprises an inset continuous line 18 parallel to the edge of the cap or the pocket. The main purpose of the embossing, however, is to secure an interlocking relation between the inner face of the pocket portion 14 and the body portion 10 so that the corner of a card or print inserted into the pocket will be firmly gripped to hold the mount thereon. This construction is illustrated in Figures 6 and 7 of the drawings in which 18 indicates the embossed or depressed line in the pocket portion 14, and 20 the corresponding embossed or depressed line in the body portion 10. The inner or lower face of the pocket portion is in engagement with the upper face of the body portion thereunder so that the inner ridge formed on the pocket by the embossing projects into and engages the depression in the body portion formed in the same way. When the corner of the card or print is inserted into the pocket, it separates the two engaging faces but the tendency of those two parts to return to a normal engaging position operates to grip the inserted corner.

In carrying out the method of making my corner mounts, I first prepare a continuous strip 30 of paper or other material suitable for the body portion of the corner, of the

exact width of the mounts. Preferably I use a thin tough paper not easily torn and coated with a suitable adhesive 32 on one side. The end of the strip is cut at right angles to its sides and the corners of the end are cut on lines 34 at an angle of forty-five degrees to the axes of the strip (Fig. 1). The two corner edges are then folded over on lines 36 also at angles of forty-five degrees with said axes into the positions shown in Fig. 2, to form flanges 38 having their coated sides 32 outermost. The two flanges together form a right-angled pocket but not in closed condition.

Next, I prepare a right-angled cap 40 which may be died or stamped out of a second continuous strip 42 of paper or other suitable material which is uncoated, the cap being of a size to cover said flanges 38 to complete the pocket. The strip 42 is preferably, when paper is used, comparatively thick, heavy and tough or may be made of double or treble layers or plies and is uncoated. In applying the cap to the flanges 38 to complete the pocket, the cap or the strip 42 from which the cap is cut is moistened and when the moistened cap is pressed down upon the flanges 38 immediate adhesion results. I have found in this connection that the moisture must be applied to the cap and not to the adhesive coated flanges for if the application is made to the latter it will be practically impossible to place the cap in proper position on the flanges and to secure a proper adhesion between the two except by great care and a long continued pressure. When the cap alone is wet permanent and complete adhesion may be secured by a quick blow or pressure exerted for but an instant.

The application of the cap may be accomplished by any suitable die or stamp and the embossing of the pocket portion of the mount should preferably be done in the same operation because it is much more effective and permanent when performed on a wet or moist cap. The cap being of comparatively heavy material takes the impression of the embossing better when wet and holds it better because it dries in that form. The embossing therefore tends to stiffen the cap.

In Figures 6 and 7 the edge of the cap is shown as just a trifle larger than the flanges. I have found that if the cap overlaps all sides the exposed surfaces and edges of the flanges, one sixty-fourth of an inch approximately, and the surface of the embossing die is formed to press the pocket portion of the corner into the shape in cross-section shown in said figures, that the edge of the cap on all sides is bent down over and conceals the edges of the flanges. This is important especially when a cap having a dull finish is used because the adhesive coated side of the mount has a high gloss and unless the cap laps down over the lines of fold of the flanges, a thin line of gloss

is visible on those edges and ruins the appearance of the mount. Since practically all mounts of this form are made with caps having dull or unfinished surfaces for use in mounting prints or photographs the importance of avoiding a visible line of gloss in the completed mount is apparent for no matter how thin the line may be, it becomes especially noticeable in the mounting of a photograph.

At the time the mount is completed by the application of the cap, it may be severed from the continuous strip along the line 16 which leaves the end of the strip in the exact form shown in Fig. 1 ready for the making of the next corner mount.

Although my method may be performed by hand with the use of a few simple utensils, yet I have found that certain steps of my method can be carried out with most advantageous results by the machine shown and described in an application for United States Letters Patent filed by me June 17, 1924, Serial No. 720,540.

In the use of mounts constructed in accordance with my invention, four mounts are placed on the four corners of the object to be mounted with the corners fully inserted in the mounts, the adhesive coated backs of the mounts moistened with a small sponge or, better still the surface on which the card is to be mounted is moistened at the points where the mounts are to be affixed and the card is then laid on the supporting surface and the mounts pressed down. If the supporting surface is moistened rather than the adhesive coated backs of the mounts a perfect bond between the two is secured with very little pressure and that exerted only for an instant. Furthermore, the card cannot slip to one side or the other when the backs of the corners are wet and pressure is applied.

The fact that the completed mounts are not flat so far as the pocket portion is concerned but are in the shape shown in Figure 6 is of importance because it facilitates in such a large measure the mounting of cards or photographs in an album or on a similar supporting surface. This shape is given the mount by the embossing die at the time the corner cap is applied while the cap is moist and consequently the mount dries in that shape which is thereby made permanent. At the same time, the pressure of the die tends to press all the layers of the pocket portion of the mount into close contact as shown in Figure 6. When the corner of a card or photograph is inserted in the pocket portion of a mount, the body portion 10 of that part of the mount is separated from the pocket but the tendency of the mount to return to its original position results in the corner of the card or photograph being firmly gripped. This gripping action is sufficiently strong so that the card with the mounts thereon may be handled with impunity without disturbing

the mounts on its corners and I have found that this gripping action is so strong that the mounts are not disturbed even when the card is shaken violently in an attempt to displace the mounts. The amount of labor and time required for mounting cards or photographs in an album, for instance, with the use of mounts made in accordance with my invention is greatly reduced; so much reduced and the operation is rendered so simple and may be performed with such rapidity that it becomes a pleasure rather than an arduous task.

It is to be understood that my invention is not to be limited to the exact form of construction and the exact method herein shown and described since both may be varied to certain extents within the purview of the following claims.

20 What I claim is:—

1. A corner mount comprising a body portion coated with adhesive on its reverse face and a right-angled pocket on its uncoated side, said pocket being made up of two edges 25 of said body portion turned over into contiguous right-angled relation and a right-angled cap secured to said flanges, said cap and said flanges being provided on the inner face of said pocket with inwardly projecting ridges interlocking with corresponding depressions in the body-portion of said mount in order to grip the corner of the object to be mounted when inserted in said pocket.

2. The method of making a corner mount 35 consisting in preparing a continuous strip of material coated on one side with adhesive and suitable for the body portion of the mount, forming the end thereof in a manner to permit the formation thereon of two 40 flanges in right-angled relation to each other and at angles of forty-five degrees to the longitudinal axis of said strip, turning over the two corner edges of the end of said strip to form two flanges in contiguous right-angled 45 relation to each other, then pressing a moistened right-angled cap on said two flanges to form with said flanges a corner-receiving pocket on said body portion and simultaneously severing said mount from said continuous strip in such manner as to leave the 50 end of said strip suitably shaped for the formation of the next succeeding mount.

3. The method of making a corner mount 55 consisting in preparing a continuous strip of material suitable for the body portion of the mount, said strip being coated with adhesive on one side, cutting off the corners of the end of said strip at angles of forty-five degrees with the axes of said strip, turning 60 over the two corner edges of the end of said strip toward the uncoated edge of the said strip to form two flanges in contiguous right-angled 65 relation to each other, pressing a right-angled cap in moistened condition upon the adhesive coated outer faces of said flanges

to form a pocket on the front face of said body strip and simultaneously severing said mount from said continuous strip in such manner as to leave the end of said strip suitably formed for the next mount.

4. The method of making a corner mount 70 consisting in preparing a continuous strip of material coated on one side with adhesive, squaring the end of said strip and cutting off the two corners of said end at angles of forty-five degrees to the longitudinal axis of said strip, folding over the corner edges of said strip to form two flanges in contiguous right-angled relation to each other with the coated sides outermost and at angles of forty-five degrees to the longitudinal axis of said strip, preparing a right-angled cap of uncoated material, moistening said cap, pressing said cap while moistened down upon said flanges to entirely cover the same and to form with said flanges a corner-receiving pocket upon the uncoated side of said strip and then severing said mount from said continuous strip by a cut which leaves the end of said strip in proper shape for the formation of the 80 next succeeding mount.

5. The method of making a corner mount 85 consisting in preparing a continuous strip of material of the exact width of the body portion of said mount and coated with adhesive on one side, the end of said strip being cut straight across and having its two corners cut on angles of forty-five degrees with the longitudinal axis of said strip, turning over the two corner edges of the end of said strip toward the uncoated side thereof to form two flanges in contiguous right-angled relation to each other and at angles of forty-five degrees to the longitudinal axis of said strip, forming a corner-receiving pocket on 95 the end of said strip by pressing a right-angled cap of moistened material upon said flanges and then severing said mount from said continuous strip in such manner as to leave the end of said strip suitably shaped 100 for the formation of the next succeeding mount.

6. The method of making a corner mount 105 consisting in preparing a continuous strip of material suitable for the body portion of the mount, said strip being coated with adhesive on one side, turning over the two corner edges of the end of said strip to form flanges in contiguous right-angled relation to each other and at angles of forty-five degrees 115 to the longitudinal axis of said strip with their coated faces outermost, pressing a right-angled cap while in moistened condition upon the adhesive coated faces of said two flanges to form a corner-receiving pocket, and simultaneously embossing said pocket portion of said mount to form internally projecting ridges upon said cap and flanges and corresponding depressions in the body portion of said mount for gripping the corner of the 120 125 130

object inserted in said pocket and severing said mount from said continuous strip with a cut which leaves the end of said strip properly shaped for the formation of the next 5 succeeding corner.

7. A method of making a corner mount consisting in forming a corner receiving pocket on a strip of material coated on one side with adhesive by turning over the edges 10 of the strip to form flanges in right-angled relation to each other with their adhesive surfaces exposed and by applying and affixing a moistened right-angled cap to said flanges and simultaneously embossing said corner receiving pocket to form internally projecting ridges upon the cap and corresponding depressions in the strip for gripping the corner of the object inserted in the pocket. 15

8. A method of making corner mounts consisting in forming a corner receiving pocket on a strip of material coated on one side with adhesive by applying and affixing a moistened right-angled cap thereto and simultaneously embossing said corner receiving pocket to 20 form internally projecting ridges upon the cap and corresponding depressions in the strip for gripping the corner of the object inserted in the pocket and severing said completed corner from said strip simultaneously 25 with the affixing of said cap to form said pocket.

9. A method of making a corner mount consisting in forming a corner receiving pocket on a strip of material coated on one side with adhesive by turning over the edges of the 30 strip to form flanges in right-angled relation to each other with their adhesive surfaces exposed and by applying and affixing a moistened right-angled cap to said flanges and embossing said corner receiving pocket to form 35 internally projecting ridges upon the cap and corresponding depressions in the strip for gripping the corner of the object inserted in the pocket and severing said completed corner from said strip simultaneously with the 40 affixing of said cap to form said pocket.

10. A corner mount comprising a body portion coated with adhesive on its reverse face and having two of its edges turned over upon 45 its uncoated side in a contiguous right-angled relation, said body portion being provided with linear depressions in its body portion underneath said turned over edges and a right-angled cap adhesively secured to said 50 turned over edges to form a pocket upon the uncoated side of said body portion; said cap and said turned over edges being provided with inwardly projecting linear ridges interlocking with the depressions in the body portion 55 of said mount to grip the corner of the object to be mounted when inserted in said pocket. 60

11. The method of making a corner mount consisting in forming a corner receiving pocket on the front face of a strip of thin

paper coated on its reverse face with adhesive by turning over upon its front face edges thereof in a contiguous right-angled relation, moistening a second strip of paper, cutting out a right-angled cap from said second strip, 70 then pressing said cap while in moistened condition to said turned over edges and simultaneously therewith forming internally projecting ridges in said cap and edges and corresponding depressions in the body portion of said strip and after severing said corner from said strip permitting it to dry. 75

12. A paper corner mount comprising a body portion coated with adhesive on its reverse face and having two of its edges turned over upon its uncoated side in a contiguous right-angled relation and a right-angled cap adhesively secured to said turned over edges to form a pocket upon the uncoated side of 80 said body portion; said body portion and said pocket having ridges formed on one of said members interlocking with depressions formed in the other of said members for gripping the corner of an object when inserted in said pocket. 85

13. A paper corner mount comprising a body portion coated with adhesive on its back face for attaching it to a supporting surface and a right-angled pocket portion on the front face of said body portion, said pocket portion being of double thickness one of which is integral with said body portion and said body portion and said pocket portion having ridges formed on one of said portions interlocking with depressions formed in the other of said portions for gripping the corner of an object when inserted in said pocket. 90 95 100

In witness whereof I hereunto set my hand this eleventh day of March, 1926.
